VULCANIZER

Ralph E. Lawrence, Fresno, Calif.

Application August 7, 1937, Serial No. 157,966

2 Claims. (Cl. 219—19)

This invention relates to vulcanizers and an object of the invention is to provide a vulcanizer characterized by simplicity of construction, and consequent low cost production.

5 The invention together with its objects and advantages will be best understood from a study of the following description taken in connection with the accompanying drawings wherein:

Figure 1 is a perspective view of the vulcanizer.

10 Figure 2 is a fragmentary detail sectional view of the vulcanizer, and

Figure 3 is an exploded view showing certain elements of the vulcanizer in perspective and separated.

15 Referring to the drawings by reference numerals it will be seen that in the preferred embodiment thereof the vulcanizing tool comprises a plate 5, preferably of aluminum and provided at its marginal edges with upturned flanges 6.

20 For disposition on the plate 5 within the confines of the flanges 6 are a pair of plates 7 and 8 respectively of mica.

Disposed between the mica plates 7 and 8 is a plate 9 of smaller dimensions than the plates 7 and 8 and also of mica.

25 Wound on the plate 9 are strips 10, such as resistance ribbons. At one end thereof the ribbons 10 are electrically connected with an eyelet 11 of conductive material. Eyelet 11 has one end arranged within an opening provided therefor in the plate 9 and has said end upset to clench the aforementioned ends of the resistance ribbons 10.

30 The eyelet 11 also extends through a centrally positioned opening 12 provided in the upper mica plate 8, and sleeved on the upper end of the eyelet 11 is a washer 13 that is held in position through the medium of bendable tongues 14 provided on the upper end of the eyelet 11 at diametrically opposite sides of said eyelet.

35 Superimposed on the mica plate 8 is a plate 14 preferably of sheet iron, and at the center thereof plate 14 is provided with an apertured pressed out formation 15.

Plates 5, 7, 9, 8 and 14 are secured in assembled 40 position by bending the flanges 6 inwardly over the marginal edges of the plate 14 as at 16 whereby to provide for the plate 5 internal marginal channels which receive the edges of the plates 7, 8 and 14, as clearly shown in Figure 2.

45 Secured within the aperture in the formation 15 of plate 14 is a washer 17 that is externally grooved to receive the edge of the formation 15 defining the aforementioned opening in the formation 15 of plate 14.

50 It will thus be seen that the assembly just de-

scribed constitutes what may be termed a head, the same being indicated generally by the reference numeral 18.

For the head 18 there is a handle 19 of wood or other suitable material provided at one end with 5 a threaded bushing 20 formed integrally with a ferrule 21 on said end of the handle 19.

Extending through the washer-equipped apertures in the plate 14 and threaded into the bushing 20 of the handle 19 is a bolt 22 that serves to 10 secure the handle 19 in the head 18.

The bolt 22 extends through the apertured end of a contact finger 23 of brass or other suitable material, and disposed on the bolt 22 between the said end of the finger 23 and the washer 17 is a 15 washer 24 of metal or other suitable conductive material.

With the head 18 and the handle 19 assembled as shown in Figure 2 the head of the bolt 22 seats on the upper end of the eyelet 11 as shown. 20

It will also be noted that the resistance ribbons 10 have the free ends thereof reversely bent about opposite edge portions of the plate 7 to be clamped between the plate 7 and plate 5 whereby said ribbons 10 are securely held in wrapped condition 25 about plate 9.

Further in accordance with the present invention there is provided for the head 18 an attachment 25 to be used for buffing the inner tube or other articles to be patched prior to the application of the patch. In the present instance the attachment 25 is in the form of an angular plate 26 of metal or other suitable material and provided on a flange thereof contacting the outer face of one of the flanges 6 with teeth 27 or 30 otherwise to provide a working surface for buffing the rubber article to be patched. The other member of the plate 26 rests flatly on the inclined edge of the associated flange 26 and is 35 reversely bent as at 28 to provide a channel or 40 groove for receiving said edge of the associated flange 6 whereby the buffing element 25 is securely associated with the head 18.

In actual practice the inner tube or other rubber article to be patched is first buffed by bringing the attachment 25 into use in a manner thought to be obvious.

The patch is then properly positioned on the tube or other article. Next the operator places the brass contact finger 23 in engagement with 50 that terminal post of the generator connected to the battery, while at the same time plate 5 is engaged with the grounded side of the generator. The tool is held in this position anywhere from one minute to a minute and a half 55

to thoroughly heat the plate 5, and when plate 5 becomes sufficiently heated it is then placed on the patch, which latter, in turn, is properly positioned over the area of the inner tube or other rubber article to be patched. It will be found that by applying the heated plate 5 to the patch anywhere from two to four minutes a good bond between the patch and the inner tube or other article to be repaired will result.

10 In connection with the above it will be appreciated that during the use of the tool it will not be necessary to have the internal combustion engine in operation since during the heating of the vulcanizer the current will be through one side of the relay, feeding the relay from one side of the battery.

15 It is thought that a clear understanding of the construction, utility and advantages of a vulcanizer of this character will be had without a more detailed description.

20 Having thus described the invention what is claimed as new is:—

1. In a vulcanizer of the character described,

a handle, a head connected to said handle, said head including a plurality of superimposed plates including a metallic plate and a pair of plates of nonconductive material, together with a heat resistance element confined between the plates 5 of said pair and a contact finger projecting laterally from the handle and having electrical connection with the resistance element through the connection for the head.

2. In a vulcanizer of the character described, 10 a handle, a head mounted on said handle, said head including a plurality of superimposed plates including a metallic plate and a pair of plates of nonconductive material, together with a heat resistance element confined between the plates of 15 said pair, and a contact finger extending laterally from said handle at said one end thereof, said contact finger being electrically connected with said resistance element and a common connection for the head and contact finger with the 20 handle.

RALPH E. LAWRENCE.
